(57) **CLAIM**

The ornamental design for a communication and sensor hub arm band, as shown and described.

DESCRIPTION

FIG. 1 is a perspective view showing the new design for a communication and sensor hub arm band. As shown, the communication and sensor hub arm band is oriented vertically;

FIG. 2 is a front view thereof;

FIG. 3 is a rear view thereof;

FIG. 4 is a side view thereof;

FIG. 5 is a top view thereof;

FIG. 6 is a bottom view thereof; and,

FIG. 7 is a perspective view thereof, shown in use.

The broken lines depict environment and are included for the purpose of illustrating only and form no part of the claimed design.
